UNITED STATES PATENT OFFICE.

FERDINAND SATTERSTROM, OF HASTINGS, MINNESOTA, ASSIGNOR TO MAGNETIC POWER TRANSMITTER COMPANY, OF FARIBAULT, MINNESOTA, A CORPORATION OF MINNESOTA.

TYPEWRITER.

1,367,991.

Specification of Letters Patent.

Patented Feb. 8, 1921.

Application filed August 17, 1917. Serial No. 186,698.

To all whom it may concern:

Be it known that I, FERDINAND SATTERSTROM, a citizen of the United States, resident of Hastings, in the county of Dakota 5 and State of Minnesota, have invented certain new and useful Improvements in Type-writers, of which the following is a specification.

The invention relates to improvements in 10 typewriters designed for writing upon sheets of paper, or upon the leaves of bound books, while the same are held in a horizontal or flat position. Machines of this type are largely used for billing purposes and 15 must be capable of writing upon large sheets of paper.

The object of my invention is to provide a machine of this class adapted for use with either large or small flat sheets of paper, or 20 with various sizes of bound books, and at the same time capable of being operated at great speed to produce accurate and neatly printed work.

The invention consists generally in electrically actuated means controlled by the 25 type keys for setting type-bar actuating rods in position to be operated.

The invention consists further in providing a machine of this class with a continuously 30 rotating shaft armature, and a co-operating rotatable magnet, electrically clutched to the shaft armature by the operation of any key of the keyboard, and furnishing the means for operating any type-bar actuating rod, which has been previously 35 set by the operation of a key.

The invention consists further in means for demagnetizing the rotating magnet and positively stopping the same at the end of 40 each revolution.

The invention consists further in the constructions and combinations hereinafter described and particularly pointed out in the claims.

45 In the accompanying drawings forming part of this specification:

Figure 1 is a plan view of a machine embodying my invention, the frame and parts of the mechanism being broken away to 50 permit showing the essential features on the single sheet of drawings.

Fig. 2 is a side elevation with a portion of the frame and paper holding platen in section.

Fig. 3 is a plan view of the type carriage, 55 the cover thereof being partly broken away.

Fig. 4 is a vertical section of the keyboard taken generally on line 4—4 of Fig. 5, but showing the key slots of the three upper rows of keys in section, and also showing the 60 insulators 76 in section, so as to expose the staggered bolts 86 with a diagrammatic illustration of the circuits that are closed through the keyboard.

Fig. 5 is a horizontal section on line 5—5 65 of Fig. 4.

Fig. 6 is a detail section and diagram showing the operative portion of the type carriage and illustrating the arrangement of a single type bar, and also showing a single 70 key on the keyboard and illustrating the electrical connection between the circuit closers operated by the key and the operating mechanism for the type bar, the parts being in normal position.

Fig. 7 is a view illustrating the same parts of the type carriage that are shown by Fig. 6, with the type bar and type in position to make an impression upon the paper.

Figs. 8, 8^a and 9 illustrate the rotating 80 magnet and parts coöperating therewith in positions differing from those shown in Figs. 6 and 7.

Fig. 10 is a detail showing the parts that are illustrated in Fig. 6 at the completion 85 of the operation but prior to the release of the key.

Fig. 11 is a side elevation and partial section of a portion of the type carriage, showing particularly the rotatable magnet and 90 the part coöperating therewith.

Fig. 12 is a vertical section on line 12—12 of Fig. 11.

Fig. 13 is a detail section on line 13—13 of Fig. 11, looking in the direction of the 95 arrow.

Fig. 14 is an elevation of the parts shown in Fig. 11, but looking at the device from the opposite side of the machine.

Fig. 15 is a detail illustrating the escape- 100 ment for the type carriage and the means for actuating the same.

Fig. 16 is an elevation and partial section of the revolving magnet.

Fig. 17 is a plan view of the escapement dogs and their supporting means.

Fig. 18 is a detail of a section on line 18—18 of Fig. 1, showing the means for holding the paper in position on the platen.

Fig. 19 is a detail showing in section a portion of the escapement wheel and the escapement dogs in various positions.

Fig. 20 is a detail of the revolving magnet and shaft armature with which it cooperates.

In the accompanying drawings forming part of this specification, the various elements are designated throughout by similar reference characters.

Table and paper-supporting platen.

The frame or table which supports the working parts of the machine is represented in the drawings by the reference letter A. This table is preferably provided with suitable legs 2 and carries a stationary platen B upon which a sheet of paper that is to be written upon (represented by *a* in Fig. 1), may be placed and held in any suitable manner. I have here shown arranged at the left side of the platen (see Fig. 18) a clip plate 4, carried by a shaft 6 which extends to the front of the platen and is provided with a finger-piece 7. Spring arms 5 tend to hold the clip plate against the platen. By bearing down upon this finger-piece the shaft is partially rotated, and the clip plate 4 is raised. The left-hand edge of the sheet may then be inserted under the clip plate, its back edge being brought against a ledge or lining up shoulder 8.

The platen B may be of any size desired, and the size of the sheet to be written upon is limited only by the size of the platen. By employing a suitable platen the machine may also be used for writing upon the pages of bound books.

The table is also provided, near its lateral edges, with parallel rails 9, 9, which extend substantially from the front to the rear of the machine, and each rail has a series of teeth 12, forming a rack-bar on the top thereof. These teeth 12 are slightly narrower than the rail 9, thereby providing a narrow ledge 13 at the top of the rail on each side of the rack.

The keyboard.

The keyboard which, as a whole, I designate by the reference letter C is preferably of substantially rectangular form and is rigidly secured to the front part of the table in front of the paper supporting platen. This keyboard is provided with a series of keys 10, preferably arranged in banks or rows, and with a spacing key or bar 11.

The keyboard is also provided with a series of circuit closers, hereinafter described, and suitable electric conductors connect the circuit closers on the keyboard with the operating magnets on the type carriage.

Type-carriage base-frames.

Arranged upon the table or supporting frame of the machine is a rectangular frame D, which I term the type-carriage base-frame. This frame is provided with the side rails 14, 14, preferably of the form shown in side elevation in Fig. 2, and each having at its forward or front end the upwardly extending posts 15, and near its rear the shorter upwardly extending shoulders 16. The posts 15 are connected preferably near their upper ends by a transverse rod 17, preferably held in position by suitable nuts 18, and the rear ends of the side rails 14 are connected by a rod 19 held in position by suitable nuts 20. The side rails 14 and the rods 17 and 19 together form a firm and substantial rectangular frame. When the frame is in position upon the machine as shown in Figs. 1 and 2, the side rails 14 extend downward outside of and in close proximity to the stationary rails 9. This carriage is provided with wheels 21 each having a series of teeth engaging the teeth of the co-acting rack-bar 12, and with smooth faced rims 22 on each side of the gear teeth of the wheel, and these rims rest upon the ledges 13 at opposite sides of the rack-bars 12, whereby the carriage D is supported and adapted to move back and forth freely upon the rails 9. A shaft 23 is mounted at its ends near the rear end of the base-frame D in the side rails 14, and the rear wheels 21 are fixed upon said shaft 23, whereby the wheels at both ends of the shaft must move together over the rack-bars thereby causing both ends of the base-frame to move together and keeping said frame always in alinement with the rails 9 on the table. The base-frame D may be freely moved backward or away from the keyboard by merely being pushed in that direction by the operator. For the purpose of readily permitting the base-frame to be moved forward at any time the required distance to change the position of the paper in respect to the line of type to be printed, I provide a short shaft 24 upon which one of the wheels 21 is secured. This short shaft preferably carries the forward wheel 21 at the left-hand side of the base-frame. The shaft 24 is mounted in rigid bearings provided in one of the posts 15 and in a post 25 secured to the side of one of the rails 14. The shaft 24 is also provided with a ratchet wheel 26 and a hand-lever 27 is provided for the purpose of operating said ratchet wheel. An adjustable stop screw 28 and a stop lug 29

are provided for regulating the movement of said ratchet wheel. These parts are common in connection with typewriter carriages and need not be more particularly described 5 herein.

By operating the hand-lever 27 the corresponding wheel 21 is turned, and thereby the base frame of the carriage is moved forward, or toward the keyboard, a distance 10 equal to the space it is desired to provide between two lines of typewriting. Through the means already described both sides of the base-frame will be caused to move in unison. The base-frame may be moved 15 backward at any time by simply being grasped by the operator and pushed backward or away from the keyboard, and the front edge of the platen.

The base-frame is also provided with a 20 transverse rail 28 provided with a series of teeth 29, forming a rack-bar, and with a ledge 30 extending along its side and parallel with said rack-bar. This rail is secured at its ends to the rails 14, preferably by having its face clamped against the shoulders 25 16 thereon. The rail 28 forms means for supporting the rear edge of the type carriage, and also forms means for guiding said carriage transversely of the base-frame 30 during the typewriting operation, as hereinafter described.

Type-carriage frame and supporting means.

The type-carriage moves longitudinally of 35 the machine with the type-carriage base-frame above described, and it is supported upon said base-frame and is capable of transverse movements thereon. This frame consists principally of a horizontal and substantially rectangular plate 31 to the forward edge of which is secured an upright or 40 plate 32. The plate 32 is provided near its upper edge, and preferably at the longitudinal center thereof, with a stud 33 upon 45 which is mounted a wheel 34 that rests upon the rod 17 (see Figs. 1 and 2). At its rear 50 the plate 31 is provided with the brackets 35 and 36. These brackets are provided with the horizontally arranged pairs of 55 guide-wheels 37, 37, which engage the front and rear surfaces of the transverse rail 28. The bracket 35 is provided with upwardly 60 extending lugs 38 in which is mounted a short shaft 39 provided with a wheel 40 that rests upon the ledge 30 on the rail 28.

The bracket 36 is also provided with the 65 upwardly extending lugs 41 in which is mounted a short shaft 32. This shaft is provided with a loosely mounted wheel 43 70 that rests upon the ledge 30, said wheel being formed integrally with a sleeve 44 and a pinion 45, the pinion 45 being in mesh with the rack-bar 28. The sleeve 44 has a clutch face that is engaged with a corre-

sponding clutch face 46 formed on a two-part sleeve that is capable of sliding longitudinally on the shaft 42, but is compelled to rotate with the escapement wheel 48 also provided on the shaft 42. The two members of the clutch are held normally against each other by a spring 47. The clutch members may be separated when desired by a lever 47' to which is connected a push-bar 47" that extends to the front of the carriage. Any desired means may, however, be employed for separating the parts of the clutch. 75

The type carriage is provided with an escapement arranged to be vibrated by a lever 50 connected to an actuating rod 51, the means for actuating this rod being herein-after described (see Figs. 1, 3 and 15).

As shown in Fig. 15 the escapement is provided with a ratchet wheel 55 and a pivoted dog 56 engages this ratchet wheel and prevents any backward or reverse movement 85 thereof.

In Fig. 19 I have shown the different positions assumed by the dogs 49^a and 49^b of the escapement, while it is being operated to permit the escapement wheel 48 to turn 90 one tooth. As here shown the dog 49^a is formed integrally with a sleeve 49 which is secured to the upright shaft 57. The lever 50 is secured to the upper end of the shaft 57, and as said lever is oscillated the dogs 95 are vibrated laterally.

The dog 49^b is pivoted to the dog 49^a and is provided with a spring 49^c (see Figs. 15 and 17), by which, when the end of this dog is not in engagement with one of the 100 teeth of the escapement wheel, its free end will be raised into the position shown in Figs. 15 and 19.

By examining the position of these dogs as illustrated in the detail views, Fig. 19, 105 the action of the escapement dogs in permitting the escapement wheel to turn one tooth with each lateral oscillation of the dogs will be readily understood.

A type-carriage actuating spring is provided in a barrel 52 and is connected to the type carriage by a steel or other suitable ribbon or flexible connection 53.

The arrangement of a spring for moving the type-carriage in one direction, the spring being wound up as the carriage is moved by the operator in the other direction, and the action of an escapement, permitting the type-carriage to be moved by a spring, step by step, as the type bars are actuated, is 115 common in type-writers and will not herein be more particularly described.

The inking ribbon.

I have indicated by the reference letter 125 E in Figs. 1 and 7 of the drawings an inking ribbon which is arranged in position to be struck by the type above the paper as the

type are actuated. I have not thought it necessary to illustrate the means I prefer to employ for holding and feeding the ribbon, as devices for this purpose are all known in the art, and any suitable or preferred construction may be employed.

The type-bars and their operating rods.

The plate 31 of the type carriage is provided, preferably at the forward central part thereof, with a series of grooves 60, all extending on lines radiating from a common center. The plate 31 is preferably made considerably thicker at the portion in which the grooves are formed than it is in its other parts, and a semi-circular opening is provided toward which this thicker surface slopes. The grooves 60 are formed in this thickened portion of the plate, as clearly shown in Figs. 3 and 11 of the drawings. A type-bar 61 is provided in each of these grooves (see Figs. 6 and 7), and these bars are provided at their free ends with the desired type 62. There are as many of these pivoted type-bars as there are type in the machine. The type-bars 61 stand in the position shown in Fig. 6 of the drawings and they swing downward in their respective grooves until the type strike the ribbon over the paper as illustrated in Fig. 7. A type-bar actuating rod 63 having a notch or slot 64 near its upper end is connected to the end of each of the type bars 61. A spring 65 is connected to each of the rods 63 and to the plate 31. The upper end of each of the rods 63 engages a guide slot 65 in the stationary guiding plate 66.

Arranged in the rear and opposite each of the type bars 61 is an electromagnet 67 provided with pole-pieces 68, and a lever armature 69 is pivoted to the rear of each of the magnets 67 and its upper end is connected to the rod 63 by a link 70.

Arranged in suitable bearings on the type-carriage is a vertically movable standard 71 carrying a horizontally extending yoke or type bar actuator 72, having at its outer edge a horizontal rib 73. This rib 73 stands in close proximity to the slots 64 in the rods 63 (see Fig. 6) when the type bars are elevated and the rods are in the normal position shown in Fig. 6. When the parts are in this position vertical movement of the standard 71, the yoke or type bar actuator 72 and the ribs 73 does not cause any movement of the rods 63 and type bars 61, but if, when the standard 71 is moved upward, any one of the rods 63 has its notch 64 in engagement with the rib 73 on the yoke or type bar actuator 72, as illustrated by dotted lines in Fig. 6 and by full lines in Fig. 7, such movement of the standard 71 will cause the type-bar, whose operating rod is thus engaged, to be quickly moved from the position shown in Fig. 6 to the position shown

in Fig. 7, thereby causing the character represented by the type on such type-bar, to be printed upon the paper.

The key actuated circuit closers.

70

The keyboard is provided (see Figs. 4, 5, 6 and 10) with a series of springs 75 mounted upon insulating plates 76, and one of these springs extends beneath each of the keys 10, being insulated from the end of the spring 75 by an insulating plate 77. The springs serve to hold the keys normally in the raised position shown in Fig. 4 of the drawings. Two insulated circuit closing strips 78 and 79 extend crosswise beneath each row of springs 75. The strips 78 and 79 are insulated from each other and the strips 78, for the several rows of keys, are connected by the conductors 80 and 81, with a battery 82, to which is connected a grounded conductor 83. A conductor 84 is electrically connected with each of the springs 75, and extends to and is connected with the corresponding electromagnet 67 to which a grounded conductor 85 is connected. With this arrangement of parts when any one of the keys 10 is depressed, to the extent indicated by dotted lines in Fig. 6, its spring 75 is brought into contact with a conducting strip 78 and the circuit is closed through the corresponding magnet 67. This magnet then pulls the armature 69 into the position shown by dotted lines in Fig. 6, and causes the corresponding rod 63 to engage, through its notch 64 with the rib 73 on the yoke or actuator 72, thereby putting the corresponding keybar in position to be moved by the vertical movement of the yoke or actuator 72, as hereinbefore explained.

90

When the key that has been depressed is released by the removal of the finger of the operator therefrom, it is raised by the corresponding spring 75 to its original or normal position, and this movement breaks the circuit formed through said spring and the conducting strip 78. I have shown a plate of insulating material 76 to which all of the springs 75, for a single row of keys, are secured. I have here shown each spring held in place on the insulating plate by a small bolt 86, provided, beneath the plate, with a nut 87 and forming a binding post with which the corresponding conductor 84 is connected. Any suitable means may, however, be employed for holding and insulating the springs and for connecting the conductors 84 therewith.

110

The continuously moving motor.

125

The machine is provided with a suitable continuously running motor, which I have designated by the reference letter F. I prefer to employ a suitable electric motor as shown in Figs. 1, 2, 11 and 12 of the 130

drawings, that is mounted upon a bracket 90, suitably supported by the plate 31 of the type-carriage frame. The motor is provided with a shaft 91 that projects preferably in a horizontal direction over the center of the type-carriage, and this shaft is preferably provided with a soft metal sleeve secured thereto, and rotating therewith (see Fig. 13). The motor F is connected with a suitable source of electric energy by suitable conductors (not shown).

While I prefer to employ an electric motor for rotating the shaft 91, I do not limit myself thereto, as any suitable motor that may be continuously operated at a uniform speed to continuously rotate a shaft may be employed.

The rotatable magnet.

Arranged above the shaft 91 and parallel and in close proximity thereto is a rotatable magnet G, which is energized each time one of the keys 10 is depressed. When this magnet is energized it moves against and is clutched to the rotating shaft armature and is caused to rotate therewith, to the extent of one complete revolution. The magnet is mounted upon a freely rotating shaft 93 which is provided with a crank disk 94 and a crank pin 95. The crank pin 95 is connected by a connecting rod 96 with a stud 97 on the vertically movable standard 71. The rotatable magnet is energized by the closing of a circuit through the insulated contact strip 79, by the further movement of any key 10 after the closing of a circuit through the insulated strip 78. In other words the first movement of the key closes the circuit through the magnet 67 and a further movement of the same key, bringing the spring 75 into the position shown in Fig. 10 of the drawings, closes the circuit through the rotatable magnet.

It will be seen, therefore, that each time the key is depressed the corresponding magnet 67 is first energized, to bring the type-bar actuating rod into position to be operated, and that a further movement of the key causes the rotatable magnet to be energized and clutched to the continuously rotating shaft armature whereby the yoke or actuator 72 is moved up and down and then to operate the type-bar whose actuating rod has been brought into engagement therewith.

As here shown the type-carriage frame is provided with the vertical standards 98 and 99, the upper portions of these standards being preferably off-set and curved as shown in Figs. 12 and 13 of the drawings. Pivot to the upper ends of these standards is a bar 100 which carries the laterally projecting heads 101. These heads are nearly circular in form and they provide bearings for the shaft 93. The magnet G is prefer-

ably formed of a metal spool 102 mounted upon the shaft 93, and having a suitable conducting coil 103 wound thereon. I also preferably provide disks 104 of insulating material arranged upon the shaft 93 against the ends of the spool, these disks being preferably of the same size and the diameter as the ends of the spool (see Fig. 16). These disks 104 are not necessary to the operation of the machine and may be omitted if desired.

The bar 100 is provided with a tail piece 105 (see Fig. 9) to which a spring 106 is connected. This spring has its opposite end connected to the standard 98 and it tends to rock the bar 100 on its pivot and thereby to raise the magnet from the shaft armature 91. The crank disk 94 on the end of the shaft 93 has a notch 107 in its periphery and a pivoted dog 108 is provided having a lug 109 adapted to engage said recess 107. To insure the lug 109 engaging the recess 107, and not jumping over the same, I prefer to cut down the edge of the disk on the side of the notch 107, over which the lug 109 passes as it enters said notch (see Fig. 9). A spring 110 is connected to the dog 108 (see Fig. 9) and to a pin 111. This pin tends to hold the dog snugly against the edge of the crank disk so as to insure the lug 109 entering the notch in the edge of the crank disk. For increasing and decreasing the tensions of the spring 110 I provide preferably special means hereinafter described.

I also provide on the shaft 93 a cam 112, the edge of which is in the form of a radially extending lug. A block 113 is pivoted on a suitable support and this block has an upward extension 113' which projects into the plane of the cam 112 and is engaged by said cam, which action rocks the block 113 upon its pivotal support. The block 113 carries the insulated contact springs 114 and 115, as shown in Fig. 8 of the drawings. An insulating block 117 is mounted on the bar 100 and carries a contact spring 118 that is in contact with the ring 119 on one end of the rotatable magnet (see Figs. 4 and 13). This ring is connected to the conductor 103 of the magnet.

The insulating block 117 has preferably a recess extending through it with a contact screw 116 projecting through one wall of the recess. A contact point 120 is provided on the spring 118 (see Fig. 4). The contact springs 114 and 115 project into the recess in the block 117 and stand opposite the contact screw 116 and point 120, as clearly shown in Figs. 4, 6, 7, 8 and 10. When the end of the projection 113' on the block 113 is engaged by the cam 112, the block 113 is rocked and moves the contact spring 114 into engagement with the end of the contact screw 116, as illustrated in Figs. 8 and 10.

of the drawings. When, however, the end of the projection on the block 113 is not engaged by the cam 112 the end of the contact spring 114 is out of contact with the lower end of the screw 116, and the end of the contact spring 115 is in engagement with the contact point 120 on the spring 118, as illustrated in Figs. 4, 6 and 7. A spring 124 is mounted on a bar 125, that is connected to the standards 98 and 99, and this spring engages a heel or lug 126, provided on the block 113, thereby tending to rock the block 113 so as to hold the contact spring 115 at all times in engagement with the contact point 120, while permitting it to be moved away when the cam projection 112 passes the upwardly extending projection 113' on the block 113.

Secured to the block 100 is a plate 127 carrying a pair of small hangers 128, and an electro-magnet 129 is mounted in these hangers (see Figs. 8, 10 and 14). An armature 130 for this magnet is secured upon a small rock shaft 131. The dog 108 is loosely mounted upon the shaft 131, and the pin 111 is inserted in the shaft 131 and extends through a slot in the hub of the dog 108 (see Fig. 6). To the end of the pin 111 is connected the spring 110, which is also connected to the dog 108. The lug 109 on the dog 108 rides on the edge of the cam disk 94 while the current is passing through the rotatable magnet. When the projection 112 engages the upwardly extending projection 113 on the block 113 the current is broken through the rotatable magnet and as the spring 114 engages the end of the contact screw 116 the current is passed through the magnet 129 by means of the conductor 132 (see Figs. 8 and 14). This causes the armature to be drawn toward the magnet 129 rocking the shaft 131 slightly upon its axis and moving the pin 111 with said shaft thereby increasing the tension on the spring 110. This occurs just at the instant the projection 109 on the dog 108 comes opposite the recess 107 in the edge of the cam disk 94, thereby causing said projection to be quickly and firmly drawn into said recess and positively stopping the rotating movement of the magnet.

The purpose of this is to prevent any overrun of the rotating magnet after the circuit is broken and the magnet has been demagnetized. As the magnet rotates very rapidly it might slightly over-run if this positive stop was not provided.

The circuit for the magnetic clutch.

By referring to Fig. 4 of the drawings the path of the electric current for energizing the rotating magnet, and the magnet which applies the positive stop to said rotating magnet, may be readily traced. As here shown conductors 133 extend from the

contact strip 79 to the insulated block 134 secured upon the rocking block 113, and are electrically connected with the contact springs 114 and 115. Normally the spring 115 is in contact with the contact point 120 on the contact spring 118, so that when any key is depressed a sufficient distance to bring its spring 75 in contact with both of the strips 78 and 79, the rotatable magnet will be energized, the path of the current being 75 in this instance from the battery 82 through the conductors 81 and 80 to the contact strip 78, through the spring 75 to the contact strip 79; through one of the conductors 133, the spring 115 and the spring 118 to the ring 119, 80 thence through the coils of the magnet to a ground conductor 135. As the rotatable magnet approaches the end of a single revolution the contact spring 114 is moved against the end of the contact screw 116, and the spring 115 is now switched off from the rotatable magnet and through the small magnet 129. As this magnet is energized its armature 130 is drawn toward it and the shaft 131 is rocked thereby insuring the engagement of the lug 109 on the dog 108 with the recess 107 in the crank disk 94, and positively stopping the rotatable magnet at the right point. When the operator releases the key the circuit through the magnet 129 is 95 broken and the parts are returned to their normal position, ready for the next operation.

As the shaft 131 is rocked back to its normal position the tension on the spring 110 is relieved and the dog 108 is restored to its normal position indicated in Fig. 6 of the drawing, with its lug 109 out of engagement with the recess 107 in the crank disk. The rotatable magnet is, therefore, free to move 105 again as soon as a current is passed through its coils and it is again energized and clutched to the constantly running shaft armature.

Means for operating the escapement.

I have already described the construction of the preferred form of escapement, and have stated that it was operated by means of a rod 51. This rod as shown in Fig. 15 115 of the drawings is connected to the connecting rod 96, and as the upper end of this connecting rod is connected to the crank pin on the disk 94, said connecting rod not only has an up and down motion but its upper 120 part has a to-and-fro or side-to-side motion. This movement imparts a longitudinal reciprocation to the rod 51, which gives a rocking motion to the upright shaft 57 and operates the escapement in the manner hereinbefore described. By this means the escapement is operated each time the rotatable magnet is caused to make a revolution, and as hereinbefore explained, each time the escapement is operated the type carriage is 130

permitted to move one space from left to right.

The spacing device.

5 It is frequently desirable to operate the escapement so as to permit a movement of the carriage without operating any of the type bars. To do this with this machine it is only necessary to close the circuit through 70 the rotatable magnet without having first brought the operating rod of any type-bar into position to be engaged by the vertically moving yoke 72. To accomplish this purpose I provide a spacing key 11 arranged 75 to move a spring 141 into contact with two of the contact springs 78 and 79, without closing the circuit through any one of the magnets 67. By this means the escapement will be operated so as to permit the type- 80 carriage to be moved one space without any character being printed on the paper. By repeating the operation of the space key the carriage may be moved as many spaces as desired. 85

25

General operation.

The general operation of the machine will, it is believed, be understood from the foregoing description. There are, however, some 30 features of the invention that are especially valuable and that should be emphasized.

In ordinary typewriters where there is a direct connection between the keys and the type bars, there is considerable elasticity in the touch of the operator. This prevents any undue pounding of the parts of the machine. Where, however, it has been attempted to operate the type bars by any 35 mechanical power that is simply controlled from the keyboard, it has been found difficult, especially where metal is brought in contact with metal, to prevent the parts from being pounded or jarred to pieces. 40

In my invention, while the type are operated by power independent of the power exerted by the operator and applied through the contact of metal with metal, no undesirable results are experienced, owing to the fact that there is a slight slippage in the 45 magnetic clutch formed by the contact of the rotating magnet, and the constantly rotating shaft armature. This slippage is just sufficient to prevent any undue pounding of the parts of the machine when the type bars are operated by the vertical movement 50 of the standard 71 and the yoke 72.

In operating the machine the electric motor is preferably run at a speed of about 55 seventeen hundred revolutions per minute, and the rotatable magnet is normally held about .002" above the shaft armature. At the beginning of the operation the yoke or actuator 72 will be at its lowest position. When a key is depressed the first contact 60 that is made will cause one of the type bar

operating rods to engage the vertically movable yoke. A further depression of the key will close the circuit through the rotatable magnet as already explained and will cause this magnet to be clutched to the continuously rotating shaft armature, thereby raising and lowering the yoke and operating the type-bar whose operating rod has been engaged with said yoke. It is at this point in the operation that the slight slippage 70 referred to takes place. Instead of having an unyielding connection between the yoke and the means for applying power thereto to reciprocate it, I provide in the devices described means that permit a slight slippage 75 between the vertically movable standard and the continuously rotating shaft. The electric clutch herein described permits this slippage, which contributes very largely to the successful operation of the machine. 80 85

Moreover, it will be noted that the rotatable magnet when not in operation is absolutely free to move as soon as power is applied to it, and when current is passed through its coils the attraction between the 90 poles of the magnet and the continuously rotating shaft armature causes the magnet to be clutched to the armature and to rotate therewith. It is at this point in the operation that the slippage above referred to 95 occurs, and the action of the parts is much softer and devoid of the jerk that would be experienced if a positive connection, such as gears, was provided between the rotating shaft and the means for moving the standard and yoke vertically to operate the type bars. 100

As the shaft armature is formed of soft steel and as the rotatable magnet is clutched closely to said shaft, each time the magnet 105 is energized, there might be a tendency to cause the poles of the magnet to produce grooves circumferentially in the soft steel shaft armature. I overcome this however, by providing the disks 104 of insulating material at the ends of the magnet of substantially the same diameter as the ends of the spool forming the pole pieces of the magnet. These disks of insulating material come in contact with the surface of the shaft armature and prevent any grooves being formed therein by the contact of the pole pieces of the magnet with said armature. 110 115

Another important feature of the machine is found in the arrangement of the rotatable magnet and the small controlling magnet that operates the lock for the rotatable magnet. 120

The rotatable magnet cannot be energized or caused to rotate until after the appropriate key-rod has been brought into position to be engaged by the actuating yoke of the machine. The action of the rotatable magnet in moving the yoke must take place after the appropriate type-bar operating 125 130

rod has been put into position to be engaged by the vertically reciprocating yoke.

As soon as one of the magnets for moving the type-bar actuating rods has been energized and has performed its function of moving such rod into position to be engaged by the yoke, the rotatable magnet is energized and clutched to the constantly rotating shaft armature as already described, 10 and makes a complete revolution with said shaft armature. When this complete revolution of the rotatable magnet has been practically completed the current is switched off from the rotatable magnet and 15 onto the stationary magnet that actuates the stopping device. As soon as this last named magnet has been energized it puts the stopping device in position to stop the movement of the rotating magnet. When the 20 movement of the rotatable magnet is stopped the current is cut out of both magnets, upon the release of the key, and both magnets remain dead until they are energized again in succession. It is impossible to energize 25 the stopping magnet until after the rotatable magnet has been energized and has operated.

It will, therefore, be seen that the three magnets, all of which have the circuits 30 closed through them by the depression of any character key, must be energized and must act in succession, the magnet that moves the type-bar operating rod into position to be moved by the reciprocating yoke being first energized, the rotatable or clutch magnet being next energized, and finally the magnet for stopping the rotatable magnet being last energized. These parts will, 35 therefore, perform their functions in order, one after the other, and at the close of the 40 operation, or when the clutch has been demagnetized and stopped, the parts will be in position for another operation, which will be brought about by the depression of any key. After these magnets have been energized in succession and the operation of 45 printing from one of the characters carried by the key-bars has been completed, no further operation can be obtained until the 50 operated key has been released, and has been returned to its normal position by the resiliency of its contact spring 75.

The machine can then be operated again 55 to print another character by the depressing of the same key or any other key of the machine.

I believe that I have also made a desirable 60 and valuable improvement in connecting the escapement device to the connecting rod, so that the escapement dogs are moved laterally in both directions by power from the rotating shaft.

It is customary in typewriters to move the 65 escapement dogs in one direction by power applied by the operator through the keys,

and to put a spring under compression or tension at the same time which will move the escapement dogs in the opposite direction. This makes it necessary to employ a spring of considerable power, and the escapement must be operated in one direction against the force of this spring. By connecting the actuating rod for the escapement dogs to the connecting rod 96, the longitudinal reciprocation of the rod 51 in both directions is obtained from the continuously 70 rotating shaft, and the escapement dogs are moved in both directions by power, and I obviate the employment of a spring to move the escapement dogs in one direction. 75 80

I do not limit myself to the details of construction herein shown and described as the same may be varied in many particulars without departing from my invention.

I claim as my invention:

1. In a machine of the class described, the combination with a series of type-bars, an actuating rod for each type-bar and an electro-magnet for each actuating rod, of a series of keys, means electrically connecting 90 said keys and said magnet, a rotatable shaft, means for continuously driving said shaft, an actuator, means controlled by said keys for causing any selected actuating rod to be moved into the path of said actuator, and 95 means controlled by said keys, causing said actuator to be connected with and moved by said shaft.

2. In a machine of the class described, the combination, of a series of keys and type-bars, an actuating rod for each type-bar normally in opposite position, an electro-magnet for each rod under the control of the key for moving the rod to a position where it may be operated, an actuator for 100 said rod, a constantly rotating shaft, and means under the control of any of the selected keys for operatively connecting said shaft with said actuator. 105

3. In a machine of the class described, the combination, with a series of type-bars, of a rotatable shaft and means for continuously driving said shaft, of a type-bar actuator, a series of keys, means controlled by said keys for connecting any selected type-bar with 110 said actuator, and electromagnet means, also controlled by said keys, connecting said actuator and said shaft.

4. In a machine of the class described, the combination, with a series of type bars, of a 115 rotatable shaft armature, and means for continuously rotating said armature, of a type-bar actuator, an electric clutch member arranged to connect said armature, and said actuator, and means connecting any selected 120 type-bar with said actuator.

5. In a machine of the class described, the combination, with a series of type bars, of a rotatable shaft armature and means for continuously 125 rotating said armature, of an actuator,

ator common to all of said type bars, an electric clutch member arranged to operatively connect said actuator and said shaft armature, a series of keys, and means controlled 5 by any one of said keys, connecting any selected type-bar with said actuator.

6. In a machine of the class described, the combination, with a series of type-bars, of an actuator common to all of said type bars, a 10 rotating shaft armature, an electric clutch member arranged to operatively connect said actuator and said shaft armature, a series of keys, means controlled by said keys for bringing any selected type-bar into connection 15 with said actuator, and means controlled by said keys for energizing said clutch member.

7. In a machine of the class described, the combination, with a series of type bars, of an 20 actuator common to all of said type bars, a rotating shaft armature and an electric clutch member arranged to operatively connect said shaft armature and said actuator.

8. In a machine of the class described, the combination, with a series of type bars, of an 25 actuator common to all of said type bars, a rotating shaft armature, an electric clutch member arranged to operatively connect said shaft armature and said actuator, a series of 30 keys, and means controlled by any one of said keys for energizing said electric clutch member.

9. In a machine of the class described, the combination, with a series of type bars, of an 35 actuator common to all of said type bars, a rotating shaft armature, an electric clutch member arranged to operatively connect said shaft armature and said actuator, a series of keys, means, controlled by any one of said 40 keys, for connecting any selected type-bar with said actuator, and means, also controlled by any one of said keys, for energizing said electric clutch member after the type bar controlled by the same key has been connected with said actuator.

10. In a machine of the class described, the combination, with a type-bar, of an actuator therefor, a rotating shaft armature, an electric clutch member arranged to operatively 50 connect said shaft armature and said actuator, a key, and means controlled by said key for energizing said electric clutch member.

11. In a machine of the class described, the combination, with a type-bar, of an actuator 55 therefor, a rotating shaft armature, an electric clutch member arranged to operatively connect said shaft armature and said actuator, a key, means controlled by said key for energizing said electric clutch, and means 60 automatically deenergizing said clutch member after each operation of said type-bar.

12. In a machine of the class described, the combination, with a series of type bars, of a rotating shaft armature, a rotatable electro- 65 magnet arranged in proximity to said shaft

armature, means for yieldingly retaining said magnet in its normal position, an actuator common to all of said type-bars connected with said magnet and arranged to operate any selected type-bar, a series of keys, 70 and means controlled by any one of said keys for closing a circuit through said magnet.

13. In a machine of the class described, the combination, with a series of type bars, of an actuator common to all of said type bars, a 75 rotating shaft armature, a rotatable electro-magnet arranged in proximity to said shaft armature, means yieldingly retaining said magnet in its normal position, and permitting it when energized to move into contact with said armature and to be rotated therewith, means connecting said actuator with said magnet, a series of keys, means electrically controlled by said keys to connect any selected type-bar with said actuator, and 85 means controlled by said keys for energizing said rotatable electro-magnet when any type-bar has been connected with said actuator.

14. In a machine of the class described, the combination, with a type-bar, of an actuator therefor, a rotating shaft armature, a rotatable electro-magnet arranged in proximity to said shaft armature, means yieldingly retaining said magnet in its normal position, and permitting it when energized to move into contact with said armature and to be rotated therewith, and means connected with said magnet for actuating the 90 type-bar actuator.

15. In a machine of the class described, the combination, with a type bar and an actuator therefor, of a rotating shaft armature, a rotatable electro-magnet arranged in proximity to said shaft armature, means yieldingly retaining said magnet in its normal position and permitting it when energized to move into contact with said armature and to be rotated therewith, means connected with said magnet for actuating the type-bar actuator, means for closing a circuit through said magnet, to energize the same, and means for breaking the circuit through said magnet after each operation of the type-bar.

16. In a machine of the class described, a 115 type-bar actuator comprising in combination a rotating shaft armature, a rotatable electro-magnet arranged in proximity to said shaft armature, and means for energizing said electro-magnet and causing it to rotate 120 with said shaft armature.

17. In a machine of the class described, the combination, with a type-bar and an actuator therefor, of a rotating shaft armature, a rotatable electro-magnet arranged in proximity to said shaft armature, and connected with said type-bar actuator, and means for closing an electric circuit through 125 said magnet.

18. The combination, with a movable car- 130

riage, of a series of type bars arranged upon said carriage, a rotating shaft armature arranged upon said carriage, a rotatable electro-magnet arranged in proximity to said shaft armature, means connected with said rotatable electro-magnet for operating said type-bars, a stationary keyboard provided with a series of keys, and means controlled by any one of said keys for energizing said electro-magnet.

19. The combination, with a movable type-carriage, of a series of type bars arranged upon said carriage, a rotating shaft armature arranged upon said carriage, a rotatable electro-magnet arranged in proximity to said shaft armature, a type-bar actuator common to all of said type bars and actuated by said magnet, a stationary keyboard provided with a series of keys, and electrical means, controlled by any one of said keys for connecting said type bars with said common type-bar actuator, and means controlled by said keys for energizing said electro-magnet.

20. The combination, with a type-carriage, and means supporting the same and permitting both longitudinal and lateral movements thereof, of a series of type bars arranged upon said carriage, a rotating shaft armature arranged upon said carriage, a type-bar actuator common to all of said type bars, an electric clutch member arranged to connect said actuator and said rotating shaft armature, a stationary key-

board provided with a series of keys, an electrical means controlled by any one of said keys for connecting any selected type-bar with said common type-bar actuator, and means controlled by said keys for energizing said clutch member.

21. The combination, with a movable type-carriage, a series of type bars, a power-driven shaft, a type-bar actuator common to all of said type bars, and an electric clutch arranged to connect said actuator with said power-driven shaft, all of said parts being mounted upon said carriage, of a stationary keyboard provided with a series of keys, and means controlled by said keys for connecting any selected type-bar with said common type-bar actuator, and means controlled by said keys for energizing said clutch.

22. In a machine of the class described, the combination, with a type-bar and an actuator therefor, of a rotating shaft armature, a rotatable electro-magnet arranged in proximity to said shaft armature, for actuating the type-bar actuator, means for closing the circuit through said magnet to energize the same, means for breaking a circuit through said magnet after each operation of the type-bar, and means for stopping the rotary movement of said magnet.

In witness whereof, I have hereunto set my hand this 26th day of April 1917.

FERDINAND SATTERSTROM.
